UNITED STATES PATENT OFFICE.

WILLIAM F. OLIN, OF CHICAGO, ILLINOIS, ASSIGNOR TO WILLIAM DEERING,
OF SAME PLACE.

HARVESTER-REEL.

SPECIFICATION forming part of Letters Patent No. 286,629, dated October 16, 1883.

Application filed December 26, 1882. (No model.)

To all whom it may concern:

Be it known that I, WILLIAM F. OLIN, a citizen of the United States, residing at Chicago, in the county of Cook and State of Illinois, have invented certain new and useful Improvements in Harvester-Reels, of which the following is a full description, reference being had to the accompanying drawings, in which—

Figure 1 is a front view; Fig. 2, an end view 10 as seen from the stubble end of the machine, and Fig. 3 a perspective view.

The object of my invention is to provide a reel that may be readily adjusted to any desired position, and especially to make it capable of adjustment back and forth while in its lowermost position—that is to say, may have a range of adjustment to or from the cutting apparatus in a fore-and-aft direction.

In the drawings, A is a part of the frame 20 of the harvester, and B and B' posts reaching upward therefrom, and of such length and inclination as to hold the reel when supported thereon in its proper approximate position in relation to the cutting apparatus.

C is a ring mounted upon the post B' and rigidly bolted thereto. Projecting inward to the center, and from the uppermost part of the ring, is the arm C'.

B' is a circular toothed locking-plate, rigidly 30 secured on the post B parallel with said ring C. At the center of said locking-plate B' and at the end of C' are eyes forming bearings for the rock-shaft E.

Keyed or otherwise secured to the rock-shaft 35 are the arms D and D', parallel with each other, as shown in Figs. 1 and 3, in length a little less than the inner radius of the ring C, and provided with the large eyes in their outward extremities, which form bearings for the reel- 40 shaft G.

To the left-hand end of the shaft E, as viewed in Fig. 1, and outside of the fixed locking-plate B', is adjustably secured the lever E'. The set-screw e' (see Fig. 1) serves as means 45 for such adjustment. This lever is provided with the latch e', rod e', bent latch-lever e'', and spring e, all outside of the lever, excepting a part of the latch itself, which reaches through a hole in the lever and engages in the 50 teeth in the locking-plate B'. By using a locking-plate in the form of a wheel the lever may

be moved over a complete circle and locked in any position of its movement. By unlatching the lever the reel can be moved by it instantly to any position in the arc of its movement, which movement is only limited by the arm C', which is placed in the position in which it is never necessary or even desirable to place the reel, and hence it is practically no obstruction to the free adjustment of the reel. The 55 reel-shaft is permitted to have a movement of about nine-tenths of a circle; but it is not necessary to swing it at once from one extreme to the other, and hence no extreme movement of the lever is required.

If the machine be working in grain in a condition such that the reel is required to be well upward and forward in most of its adjustments, the lever is set in relation to the shaft E and its arms, as shown in the figures.

I provide the locking-plate B' with teeth in its entire circumference, which permits its being locked in any position, whatever its direction or position of adjustment in relation to the rock-shaft E. By this means the lever 75 may be kept in a convenient position in relation to the attendant.

F is a sprocket-wheel driven by the chain f, which is connected with the harvester-gearing. In one piece with the sprocket-wheel is cast 80 the pinion f', and both revolve freely on the rock-shaft E. f' is a pinion secured to the end of the reel-shaft G, and f'' is an intermediate idle pinion. It is thus seen that the motion given the sprocket-wheel is transmitted to 85 the reel-shaft, and they revolve in the same direction.

The advantages of the construction here shown will be apparent to those familiar with the use of harvesters and need not be pointed 90 out, except to place particular stress upon the perfect freedom of vertical adjustment, whether the reel is forward of the axis of vibration or in rear of it, and also the freedom of adjustment fore and aft when low, as in operating in 95 lodged grain.

I am aware that reels have been made to vibrate upon their support, but their movements have been obstructed by the posts that support their axis. By providing the down-hanging support the reel is free to move to any desirable position, the arm C' occupying

a position in which the reel-shaft is never required to be. I am not aware that reels have been geared in the manner shown, nor that the rock-shaft has been provided with an adjustable adjusting-lever.

What I claim is—

1. The combination of the rock-shaft E, provided with the shaft-carrying arms D and D', with the down-hanging support C', substantially as described.
2. The combination of the rock-shaft E, provided with the shaft-carrying arms, with the posts B and B' or other suitable supports, the ring C, and the down-hanging support C', substantially as described.
3. The post B, provided with the circular locking-plate B², the center forming a bearing for the rock-shaft E, and the post B', provided

with the ring C, the latter having the down-hanging arm, forming a support, all combined with the rock-shaft E, substantially as described.

4. The rock-shaft carrying the reel-shaft, in combination with the adjustable adjusting-lever E' and the circular locking-plate, substantially as and for the purpose described.

5. The combination of the rock-shaft, the reel-shaft supported and vibrated thereby, and provided with the pinion, the sprocket-wheel and pinion located on the axis of vibration, and the intermediate idle-pinion, substantially as and for the purpose described.

WILLIAM F. OLIN.
